A. FORBES

TENNIS AND OTHER RACKET PRESS AND CASE, AND THE LIKE

Filed Jan. 24, 1922

UNITED STATES PATENT OFFICE.

ALEXANDER FORBES, OF HAMPSTEAD, LONDON, ENGLAND.

TENNIS AND OTHER RACKET PRESSES AND CASE AND THE LIKE.

Application filed January 24, 1922, Serial No. 531,412.

To all whom it may concern:

Be it known that I, ALEXANDER FORBES, a subject of the King of Great Britain, residing at 78 Fairfax Road, Hampstead, London, England, have invented new and useful Improvements Relating to Tennis and Other Racket Presses and Cases and the like, of which the following is a specification.

10 This invention relates to presses for tennis and other rackets and has for its object the construction of a press which is better adapted to maintain a racket in form than such presses as hitherto constructed. It has the further advantage of being neat and light and can be constructed of materials not affected by climatic conditions.

According to the invention the press is formed of a frame of metal, wood, fibre or other suitable material and of such shape approximately L or U-shape in cross section as to embrace the frame the space between the flanges of the said section serving to receive the racket frame, means being provided whereby the press is secured to retain the racket in place therein.

In a suitable arrangement for carrying out the invention the press frame is made of L-shape in cross section so that a racket 30 can be laid within the said frame and rest on one of the flanges of the section, the other flange lying parallel with and conforming to the shape of the exterior face of the frame of the racket and affording strength and rigidity. The racket is held in position by suitable clip fastenings. This form is suitable for tennis rackets and the like.

The press can also be made of two L-shaped frames with their two recesses opposed so as to provide a single recess for a single racket or for a series of rackets resting on one another and held together by a series of clamps or screws.

45 To enable the invention to be fully understood, I will describe it by reference to the accompanying drawing, in which:—

Figure 1 is a plan of a racket press constructed in accordance with the invention and

50 Figure 2 is an end view thereof.

Figure 3 is a section on the line 3—3, Figure 1.

55 a and b indicate, respectively, the two flanges of the L or U-shaped section of the

press frame which is made of a form to fit around the major portion of the head of a racket.

In the construction illustrated in the drawing the flanges a and b are disposed at right angles to each other, the flange a being in a single plane, and designed to engage the frame of the racket on one face thereof, while the flange b extends perpendicularly to the plane of the flange a and is curved so as to follow and conform to the exterior face or edge of the racket frame. The racket frame can thus be laid upon the flange a and will be surrounded by the perpendicular flange b. To secure the racket within the frame a—b, a pair of clips are employed, each of which advantageously comprises a bar c hinged at one end by a link d to one side of the frame a—b and provided at its other end with a portion designed to extend through a looped link e hinged to the other side of the said frame. The portion of the bar c which extends through the looped link e, is provided with serrated portions here shown in the form of ratchet teeth f with which a clip g hinged at one end to the link e is designed to engage so as to press the bar tightly against the upper side of the racket when laid in position within the frame, each clip g being provided with a tooth g' to engage the serrated portion of the retaining bar c and with a lever arm g² capable of being turned down into the position indicated in Figure 2 and secured in such position by a loop h slideable on the bar c to engage the outer end of the lever arm g² of the clip. By sliding the loop h out of engagement with the clips g, the latter can be disengaged from the teeth on the bars c and the latter turned on their hinges to allow of the removal of the racket from the press.

To stiffen the frame a, b the lower ends of the two sides thereof are connected together by a tie a¹ which may be integral 100 with the rib or flange a, or be separate therefrom and attached thereto in any suitable manner.

It is to be understood that my improved press may be arranged in combination with a case or the like whereby a racket can be wholly enclosed, the case at the same time also serving as a receptacle for other accessories used in playing tennis. For example, the press illustrated in the drawings would

be a suitable form to serve as a frame upon which to build such cases.

Having now particularly described and ascertained the nature of my said invention 5 and in what manner the same is to be performed, I declare that what I claim is:—

1. A racket press comprising a frame, provided with flange portions lying in a single plane and adapted to engage one 10 face of the racket, and a perpendicular flange united thereto and curved to conform to the exterior edge of the racket frame, and retaining bars extending across the frame and provided with means for se- 15 curing them adjacent to their ends to opposite portions of the said frame.

2. A racket press comprising a frame, provided with flange portions lying in a single plane and adapted to engage one 20 face of the racket, and a perpendicular flange united thereto and curved to conform to the exterior edge of the racket frame, retaining bars hinged at one end to one side of the frame and extending across 25 the frame, and clips secured to the opposite sides of the frame for detachably engaging and securing the opposite ends of said retaining bars.

3. A racket press comprising a frame, 30 provided with flange portions lying in a single plane and adapted to engage one face of the racket, and a perpendicular

flange united thereto and curved to conform to the exterior edge of the racket frame, retaining bars each having one end connect- 35 ed by a hinged link to one side of the frame and provided at the opposite end with a serrated portion, opposite portions of the frame being provided with hinged loops through which the serrated ends of the retaining bars extend, and clips pivoted to said loops for engaging the serrated portions of the adjacent retaining bar and locking 40 said bars in operative position.

4. A racket press comprising a frame, 45 provided with flange portions lying in a single plane and adapted to engage one face of the racket, and a perpendicular flange united thereto and curved to conform to the exterior edge of the racket frame, 50 retaining bars each having one end connected by a hinged link to one side of the frame and provided at the opposite end with a serrated portion, opposite portions 55 of the frame being provided with hinged loops through which the serrated ends of the retaining bars extend, clips pivoted to said loops, each clip having a tooth to engage the serrated portion of the retaining bar, and a lever arm portion, and a loop 60 slidable on each of the retaining bars for engaging the lever arm of one of said clips and holding it in locked position.

ALEXANDER FORBES.
